HOLDING DEVICE FOR ELECTRIC CABLES

Elwood D. Stoyer, Coshocton, Ohio

Application April 5, 1947, Serial No. 739,617

11 Claims. (Cl. 285—6.5)

1

This invention relates to a holding device for an electric cable. More particularly to a hollow clamp adapted to be mounted on a conventional connection box and engage the insulated exterior of a cable entering the box to enable its conductor or conductors to be readily connected to other conductors in the box.

Hollow boxes having openings through their walls and adapted to be attached to a wall or ceiling are in a very common use in providing housings for cable connections. Various devices have been provided for mounting on the box wall to engage the exterior of an entering cable to hold it in place, but so far as I am aware such devices have been difficult of operation and have frequently required simultaneous use of both hands of the operator, whereas he frequently has only one hand available for that purpose.

It is an object of my invention to provide in very simple form a hollow clamp adapted to be mounted, by a simple finger operation, in one of the openings in a wall of the connection box, and operative to hold the entering cable in place as it passes through the clamp, without troublesome manipulation by the operator. Cheapness of construction is also a feature of my invention.

Briefly, my invention comprises a hollow clamp having portions adapted to be passed through an opening in the box wall and having retaining lips to engage the inner face of such wall, one of such portions being carried by a spring arm so that its inward temporary displacement enables its lip to be inserted through the opening, the clamp carrying also means to engage the cable passed through the clamp to the interior of the box. When the cable is in place the clamp is automatically held on the box and the cable is held within the clamp.

The above features and other characteristics of my invention will be fully apparent from the disclosure hereinafter given of two embodiments of the invention illustrated in the drawings.

In the drawings, Fig. 1 is a vertical section through a connection box attached to a ceiling carrying one of my clamps holding an entering cable and showing also another of such clamps in the act of being inserted; Figs. 2 and 3 are vertical sections transversely of Fig. 1 in planes indicated by the lines 2—2 and 3—3 on Fig. 1; Fig. 4 is a fragmentary view showing the same clamp in place holding a considerably larger cable than shown in Fig. 1; Fig. 5 is a perspective of the same clamp detached; Fig. 6 is a vertical section of a ceiling box showing my clamp in a somewhat modified form holding cable en-

2

tering the box; Fig. 7 is a bottom view of the box and clamp of Fig. 6; Fig. 8 is a plan of a blank from which the clamp may be made.

In the drawings, A indicates a conventional connection box having openings a through various walls. This box is shown as attached to the underside of a ceiling indicated at B. C, C¹ or C² designates an electric cable passing into the interior of the box to be connected therein to another cable or cables.

My hollow clamp is adapted to enter any of the openings a in the box and automatically clamp itself thereto in position to receive the entering cable. I will first describe the clamp shown in Figs. 1 to 5 and thereafter the slightly modified form of Figs. 6 and 7.

The clamp 10 shown in perspective in Fig. 5 is a hollow box-like device preferably made of a single piece sheet metal by dieing and bending operations. It may be mounted on the connection box in any position, but as the flat portion 11 happens to be shown at the bottom in Fig. 5, and also in other figures, it is convenient to designate that portion as the "bottom" and the opposite portion the "top" and the other two faces as the "sides." The open face I call the "front" and the opposite face the "back."

Using such conventional designation, the bottom member 11 carries a downwardly extending lip 12 at its front edge and an inclined lip 13 extending forwardly from its rear edge into the clamp above such bottom portion. This bottom portion is also shown as carrying a pair of upstanding parallel side wings 14. At the rear edge of the bottom portion are a pair of upright arms 15 forming the back of the device and at their upper ends carrying the forwardly projecting top portion 16. This top portion is bent first upwardly and then downwardly at 17 to provide a closely doubled rib and then by a U-bend 18 finally carries the upturned lip 19.

Such a clamp is mounted in the opening a of the box by first passing the lip 12 through the opening and then pressing the portion 16 inwardly so that the lip 19 may enter the opening, after which, upon release of the pressure, the resilience of the portion 16 causes the lip 19 to pass behind the wall of the box.

Fig. 1 indicates at the left hand side the action in putting the clamp in place and at the right hand side the clamp after it has been mounted. It is accordingly a very simple and rapid action to install the clamp on the box. The side wings 14 of the clamp provide convenient smooth surfaces for grasping it, if desired, and as hereto-

fore stated it may be mounted with its so-called top or bottom or either side uppermost.

It will be noticed that the double band 17 on the spring arm of the clamp furnishes a lateral abutment engaging the outer face of the box wall and thus serves to locate the clamp in that region. In the opposite region, it is located by engagement of the front edge of the clamp with the outer wall of the box.

After the clamp has been mounted the cable may be inserted through the opening between the upright portions 15 of the back and pass out of the open front of the clamp into the connection box, as shown in the case of the cable C in Fig. 1. In this passageway the cable extends across the inwardly projecting tongue 13 and across the U-bend 18 on the other side of the cable. As shown in Figs. 1 to 5 the spring tongue 13 is formed to bite into insulation of the cable and by pressing it against the abutment provided by the U-bend 18 forms an automatic lock for the cable, so that the mere insertion of the cable causes it to be retained in proper position for subsequent connection of its conductors within the box.

Accordingly, the operator need do no more than shove the cable through the mounted clamp. The clamp then holds the cable and the cable insures the clamp remaining in position in the box. The parts can only be released by inserting a suitable tool, like a screw-driver, through the open side of the clamp between the tongue 13 and the cable.

The clamp, while small enough to have its retaining lips 12 and 19 passed into the conventional opening in the connection box, has a large enough interior to receive cables of the maximum size employed with such box, as well as the smaller cable illustrated in Fig. 1. Such larger cable is shown at C¹ in Fig. 4 and like the cable C of Fig. 1 it is retained by the edge of the spring tongue 13 engaging the cable on one side and the U-bend 18 engaging it on the other.

For some purposes it is desirable to avoid the automatic clamping of the cable upon its insertion but to make the holding more readily under the control of the operator. When that is desired I modify the clamp, as shown in Figs. 6 and 7, so that instead of the internal tongue imbedding itself in the cable I provide a tongue 20 curved downwardly at its free end to have a surface engagement with the cable. This is shown with the cable C² in Fig. 6. In this case, I force the tongue against the cable by a screw 21 threaded in the body 11 of the clamp.

As the clamp holds itself in any position selected, the screw 20 may face in the most convenient direction for the operator to clamp or release the cable as desired.

My clamp of the form shown in Figs. 1 to 5 may be made complete from a single blank of sheet metal, and the clamp of Figs. 6 and 7 may be made from such sheet metal blank with the exception of the screw threaded through the body of the blank. Such a blank is shown in Fig. 8, where the different parts bear the same reference numerals as Fig. 5. When the blank is die cut in the form shown in Fig. 8, the U-shaped slit 25 may be made at the same time and thus form the tongue 13. Also if the blank is to form the clamp of Figs. 6 and 7 the opening 26 for the screw may be made at the same time.

Another operation bends the wing portions 14 along the broken lines designated X, bends the portion 15 upwardly at right angles along the line

designated Y and bends the tongue 13 still further along such line so that it lies diagonally over the portion 11. Then the portion 16 is bent over on the line Z into approximate parallelism with the bottom 11. At some stage the so-called top portion 16 is bent on itself along lines indicated at W to produce the rib 17, and likewise at some stage the lips 12 and 19 are bent in the proper direction. The order in which these various bending steps are performed is of no special importance, and may be selected as most convenient.

It will be understood from the above description that my clamp may be very cheaply constructed. For this purpose I consider stainless steel of about 20 gauge quite satisfactory. The clamps are of light weight, easily carried to the place of use, and have ample strength. They may be instantaneously mounted in place and enable the operator with one hand to place the cable in position for the subsequent operation of making the connections.

I claim:

1. A holding device for a cable comprising a clamp open at the front and rear for the passage of a cable, an inwardly projecting integral spring portion of the clamp to engage the cable, and a pair of oppositely extending lips carried by the clamp, one of which is held by a spring leaf, whereby the lips may be passed through an opening in a supporting wall and thereafter engage the inner face of the wall.

2. A device for holding a cable comprising a clamp having a bottom portion, a top portion and a rear portion the latter with an opening through it, one of said portions having a part projecting inwardly to engage a cable passing through said opening, upward and downward projecting lips carried by the top and bottom portions, one of said portions being a spring leaf, whereby the lips may be forced toward each other to pass through an opening in a support, one of said portions having a projecting rib adapted to engage the outer face of the support.

3. A device for holding an electric cable comprising an open clamp having a portion with a lip at the front and an inwardly projecting inclined tongue at the rear, said clamp having a spring portion adapted to overlie the tongue spaced from it to receive a cable between them and carrying a lip extending in the opposite direction from the lip projecting from the first-mentioned portion.

4. A holding device for an electric cable comprising an open box-like clamp having a bottom portion with a downturned lip at its front edge and upwardly and inwardly extending tongue at its rear edge, a top portion in the form of a spring leaf having an upwardly extending lip at its front edge, and an open rear portion connecting the bottom portion on top portion.

5. A holding device for a cable and adapted to be secured to a connection box, said holding device comprising an open clamp having a pair of oppositely projecting lips, one of which is carried by a spring leaf, whereby the lips may be passed through an opening in the wall of a connection box and thereafter spread behind said wall, said clamp having an inwardly projecting abutment to engage one side of the cable passing through it and an oppositely projecting spring tongue to engage the opposite side.

6. A holding device for an insulated electric cable comprising a clamp having a passageway for a cable and provided with means for attaching

it to a connection box, said clamp having an abutment to engage one side of the cable and an inwardly projecting spring tongue to engage the other side, said tongue having an abrupt edge facing the cable and adapted to bite into the insulation thereof.

7. A device for holding in position an electric cable comprising a single piece of sheet material bent to present a bottom portion with a downwardly extending lip adapted to lie on the interior of a connection box, an open rear portion through which the cable may pass, and a spring top portion carrying an upwardly extending lip adapted to be pressed toward the bottom portion to pass through an opening in the box and thereafter lie on the inner side of the box wall, and a spring tongue carried at the rear edge of the bottom portion and extending into the clamp and adapted to engage the cable.

8. A hollow cable clamp of approximately cubical form having a bottom and two opposite sides and a rear side all connected to the bottom, and a top connected to the rear side and narrow enough to be depressible between said two opposite sides, a downwardly extending lip at the front edge of the bottom and an upwardly extending lip at the front edge of the top, the rear side having an opening and the front being open for the passage of a cable, and means carried by the clamp to engage and clamp the cable.

9. A device for holding an electric cable to a connector box comprising a bottom portion, two opposite side portions connected to the bottom portion and free at their front, rear and top, a rear portion extending upwardly from the bottom portion, a top portion projecting forwardly from the rear portion and narrower than the space between the side portions so that it may be depressed between them, a spring tongue formed out of the rear portion and bent forwardly from the lower edge of the rear portion leaving an opening in the rear portion adapted for the passage of a cable between the spring tongue and the spring top portion, a downwardly projecting lip at the forward end of the bottom portion, and

an upwardly projecting lip at the forward end of the top portion.

5 10. A hollow cable clamp formed of a single piece of resilient sheet material bent into approximately cubical form to present a bottom and two opposite sides and a rear side all connected to the bottom, and a top connected to the rear side and narrow enough to be depressible between said two opposite sides, a downwardly extending lip at the front edge of the bottom and an upwardly extending lip at the front edge of the top, and a spring tongue within the clamp adapted to engage the cable, said tongue being formed by partial severance and forward bending from the rear side, such cut out portion of the rear side providing an opening therethrough for the passage of the cable, the front being also open.

10 15. 11. A hollow cable clamp formed of a single piece of resilient sheet material bent into approximately cubical form to present a bottom and two opposite sides and a rear side all connected to the bottom, and a top connected to the rear side and narrow enough to be depressible between said two opposite sides, a downwardly extending lip at the front edge of the bottom and an upwardly extending lip at the front edge of the top, and a spring tongue within the clamp adapted to engage the cable, said tongue being formed by partial severance and forward bending from the rear side, such cut out portion of the rear side providing an opening therethrough for the passage of the cable, the front being also open.
